UNITED STATES PATENT OFFICE.

WILLIAM M. DORN, OF MIAMI, FLORIDA.

SWINGING CRIB FOR INFANTS.

1,260,161.

Specification of Letters Patent. Patented Mar. 19, 1913.

Application filed July 12, 1917. Serial No. 160,171.

To all whom it may concern:

Be it known that I, WILLIAM M. DORN, a citizen of the United States, residing at Miami, in the county of Dade and State of Florida, have invented certain new and useful Improvements in Swinging Cribs for Infants, of which the following is a specification.

My invention relates to a swinging crib for infants, and has for its primary object to improve, in general, devices of this character.

One feature of my invention resides in providing what may be termed a mobile supporting or suspending structure for the crib, to which end, I provide a wheeled carriage on which is mounted the crib supporting and suspending frame.

Another feature resides in constructing the device in a manner, whereby its parts may be readily disassembled and assembled for shipping or storing purposes, to which end, I construct the wheeled carriage and the supporting and suspending frame of detachable parts.

Another feature resides in the simplicity and cheapness of construction, to which end, the device is preferably constructed of tubular metal, parts of which being preferably connected by elbows or the like.

Another object of my invention consists in constructing the crib *per se* in an improved manner, to which end, another feature of my invention consists in providing a so-called knock-down crib, and in this way enable the crib also to be disassembled for shipping or storing purposes.

Still another feature of my invention resides in the co-operative relationship of the several parts of the device which go to make up the device as a whole.

Further features will be understood upon reference to the accompanying drawings, in which:—

Figure 1 is a side elevation of the structure;

Fig. 2 is an end view;

Fig. 3 is an end view showing the horizontal connecting member of the supporting or suspending frame showing the uprights partly in section;

Fig. 4 is a detail view illustrating the connection between the horizontal member and one of the uprights;

Fig. 5 is a detail view partly in section

showing the elbows for connecting parts of the wheeled carriage and the uprights;

Fig. 6 is an enlarged detail view of the wheel mounting;

Fig. 7 is a top plan view of the crib; and

Fig. 8 is a plan view of the several sections of the crib, showing their co-operative relationship preparatory to assembly.

Referring to the drawings in detail, 1 represents the wheels for the carriage which are preferably rubber tired and mounted in the lower ends of a pair of frame members 2 which, like the entire frame of the device, are preferably constructed of tubular metal. The mount for the wheels preferably consists of a short axle 3 having an upturned end 4 which is adapted to engage the tube through slots 5 in the ends thereof. These frame members 2 are provided with a horizontal intermediate portion about the center of which is mounted a three-way sleeve or elbow 6 which has a screw threaded vertical opening 7 and a horizontal opening 8. Into the vertical opening 7 is threaded the uprights 9. In order to add rigidity to the structure, a horizontal member 10 is threaded into the horizontal opening 8 of the elbow or sleeve 6, and a second horizontal member 11 connects the uppermost ends of the uprights 9. This horizontal member 11 is connected to the uprights 9 through the medium of pins 12 carried by the end portions of the member and adapted to be received in the tube. The crib is suspended from the horizontal member 11 preferably by a coil spring 13 connected by hooks 14 on the member 11 and the eyes 15 on the crib.

To disassemble the structure for shipping or storing, the wheels may be removed by disengaging their axles from the tubes through the openings or slots 5. The uprights may be then removed from the elbow, likewise the horizontal member 10. The member 11 may then be disengaged from the uprights. The crib may be taken down by disengaging the springs from the hooks 14.

With reference to the specific construction of the crib, as above stated, it is preferably constructed of demountable sections which, when assembled, will offer an inclosure comprising a bottom 16, end sections 17, side sections 18 and a top 19 composed of two sections. All of the sections are arranged

together as illustrated by detachable hinges 20 which preferably comprise male and female members and retaining pins. Each section is suitably screened with a fine mesh 5 wire.

From the foregoing, it will be readily seen that the swinging crib and its supporting structure may be readily disassembled for shipping or storing purposes, and when in 10 use, will offer the most convenient and practical device for its intended purpose.

I claim:

A swinging crib for infants comprising a wheeled carriage, a supporting structure for 15 the crib mounted on the carriage, said carriage comprising a pair of tubular metal frame members connected by a horizontal strengthening member, said frame members

having an intermediate horizontal portion and downwardly disposed end portions, 20 each of said end portions having a slot adapted to receive the axles of the wheels, said axles having upturned ends adapted to be received in the tubes of the downwardly disposed end portions of the frame members, said supporting structure comprising a pair of uprights detachably secured to the frame members of the carriage, a horizontal member having projecting pins adapted to be received in the tubes of the uprights 25 and a resiliently suspending means carried by said horizontal member for suspending the crib.

The foregoing specification signed at Miami, Florida, this 27th day of June, 1917. 30
WILLIAM M. DORN. 35
